CLAIM

I claim the ornamental design for a roller for a roll towel dispenser, as shown and described.

DESCRIPTION

This application is related to U.S. Des. Pat. App. Ser. No. 29/647,869, filed on May 16, 2018, entitled "Housing for a Roll Towel Dispenser," which is incorporated herein by reference in its entirety.

FIG. 1 is a top, front, right perspective view of a roller for a roll towel dispenser showing my new design within its environment of a roll towel dispenser with a front cover of the housing removed.

FIG. 2 is a front, right, perspective view of the claimed design of FIG. 1;

FIG. 3 is a front side view of the claimed design of FIG. 1; FIG. 4 is a rear side view of the claimed design of FIG. 1; FIG. 5 is a right side view of the claimed design of FIG. 1; FIG. 6 is a left side view of the claimed design of FIG. 1; FIG. 7 is a top view of the claimed design of FIG. 1; and, FIG. 8 is a bottom view of the claimed design of FIG. 1. The broken line showing of parts of the drawings is included for the purpose of illustrating use and environment and forms no part of the claimed design. The dash dot lines immediately adjacent to the claimed areas in the views represent the boundaries of the claimed design. None of the broken lines form any part of the claimed design.
